UNITED STATES PATENT OFFICE.

WILLIAM M. HEPBURN, OF DENVER, COLORADO, ASSIGNOR TO SURFACE COMBUSTION COMPANY, A CORPORATION OF NEW YORK.

CONTINUOUS CARBONIZING FURNACE.

Application filed February 15, 1928. Serial No. 88,197.

This invention relates to improvements in furnaces and more particularly to a furnace in which material may be carbonized while being moved through the furnace from one end to the other thereof.

In carbonizing furnaces it is of primary importance to secure uniform temperatures and to control the character of the atmosphere surrounding the work to be carbonized so as to prevent oxidation of the work or material to be treated. It has been found that oxidation of the material does not begin until the work is at a comparatively high temperature, for example, at a temperature of about 1300° F. and over. The present invention aims to take advantage of this fact by constructing a carbonizing furnace which shall have two distinct heating chambers, one of which chambers shall be open at the top to permit the circulation of burned gases over the work whereby the work to be carbonized may be quickly heated preparatory to its introduction into the high temperature soaking zone, and the other chamber being of the muffle type wherein the work may be maintained at a carbonizing temperature in a substantially dead atmosphere, the muffle constituting the soaking zone.

In accordance with the present invention the heating chamber into which the work to be carbonized is first introduced comprises an open top tunnel or heating chamber having a relatively thin floor beneath which fuel is burned and having relatively thin side walls between which and the walls of the furnace the combusted gases formed by the burning of the fuel beneath the floor pass upwardly for circulation about the work before passing out of the furnace. The soaking zone or chamber differs primarily from the preliminary heating chamber by having a roof in spaced relation to the roof of the furnace whereby the hot gases passing upwardly along the outer sides of the chamber will be prevented from coming into contact with the work. The combustion chamber beneath the soaking chamber or muffle is independent of the combustion chamber below the preliminary heating chamber, a wall separating them. The combusted gases leave the furnace through openings in its roof near the charging end of the furnace. By causing the gases to leave near the charging end of the furnace any tendency of the gases to

enter the muffle is effectually prevented with the result that the atmosphere within the muffle is substantially a dead atmosphere.

For a fuller understanding of the invention reference is made to the detailed description thereof taken in connection with the accompanying drawings forming part of this specification.

Referring to the drawings:

Fig. 1 is a longitudinal vertical section through the improved furnace, the view being taken on line 1—1 of Fig. 2, the view showing the furnace as provided with a recuperator above the openings through which the gases pass out of the furnace and also showing a conventional type of means for pushing the work into the furnace;

Fig. 2 is a transverse section taken on line 2—2 of Fig. 1 and showing the preferred manner of constructing the preliminary heating chamber, and

Fig. 3 is a transverse sectional view taken on line 3—3 of Fig. 1 and showing the manner of constructing the muffle.

The base of the furnace is indicated at 10 and may be of any suitable construction as may also its side walls 12 and top 14. The door through which the work to be carbonized is introduced into the furnace is indicated at 16 and the exit door at 18, these doors being suspended in any suitable manner. In front of the charging door is a bench 20 on which is arranged a suitable pusher generally indicated at 22 for pushing the work to be carbonized into the furnace. The work will usually be placed in boxes (not shown). Extending through the furnace are parallel tracks 24 so arranged that two rows of boxes may be pushed through the furnace at the same time. These tracks are suitably supported in spaced relation to the base 10 of the furnace and the space between the tracks is bridged by relatively thin floor sections 26 shown as of arched form. A series of races 28 between the tracks serve to give rigidity to the structure.

The interior of the furnace is divided into two distinct heating chambers, a preliminary heating chamber having a heating trough, the heating chamber as a whole being generally indicated by letter A and a soaking chamber or muffle generally indicated by letter B. Both of these chambers have side walls 30 extending upwardly in spaced relation with respect to the walls 12 of the

furnace proper. The chamber B is provided with a roof 32 arranged in spaced relation to the roof 34 of the furnace whereby the chamber B constitutes a muffle. Beneath the 5 floor of each chamber is a combustion chamber, the respective chambers being separated from each other by a transverse partition wall 36. These combustion chambers are shown as provided with fluid fuel burners 10 38 projecting through the end walls of the furnace. In the construction shown the burners are of a type to burn fuel oil. However, the improved furnace is equally well adapted to burn gas.

15 The central pier or support on which the central track is supported is provided with transversely extending openings 40 to permit free circulation of the burning gases beneath the floor of the furnace. The 20 combusted gases pass from the combustion chambers through a plurality of lateral ports 42 in the supports on which the side tracks 24 rest and pass upwardly into the space 44 between the chamber side walls 30 and the 25 furnace walls 12.

In the case of the preliminary heating chamber A, there is provided between the side walls 30 and the adjacent furnace walls a series of abutments 46 against which the 30 upper ends of the side walls 30 rest. The space between adjacent ends of these abutments 46 form passages 48 through which the combusted gases must pass. The effective size of these passages may be controlled 35 by shiftable blocks 50, only one of which is shown in Fig. 1. By regulating the size of the passages 48 the circulation of the combusted gases may be controlled so as to obtain a uniform temperature throughout the 40 length of the heating chamber A.

Extending downwardly from the abutments 46 are additional supports 46' for the chamber walls 30 and these supports are 45 preferably provided with openings 52 through which the combusted gases may flow, as for example, when certain of the 50 passages 48 are closed by the shiftable members 50. The combusted gases after passing through the passages 48 between the abutments 46 will be deflected downwardly from the arched roof 54 of the furnace and thereby caused to circulate within the tunnel portion of the chamber A and around the work 55 therein before passing out of the chamber. The gases pass out of the furnace through a 60 row of openings 56 arranged in the roof 54 thereof adjacent the charging end of the furnace as clearly indicated in Fig. 1. In order to utilize the residual heat contained 65 in the gases they are passed through a recuperator 58 of any approved form, said recuperator being arranged on the top of the furnace in alinement with the openings 56 in the roof thereof.

65 Referring now to the soaking chamber B,

the combusted gases after entering the space 44 between the side walls 30 of the chamber and the adjacent walls of the furnace are caused to travel lengthwise of the walls by reason of the fact that a continuous wall 70 support 60 is provided between the top of each wall and the adjacent wall of the furnace. These gases flow toward the far end of the furnace and pass upwardly through a passage 62 adjacent the end of the chamber 75 from whence they circulate over the roof 32 of the chamber and flow toward the charging end of the furnace and out through the openings 56 in the roof 54 thereof as previously described in connection 80 with the preliminary heating chamber A. While the heating chamber B is in effect a continuation of the heating chamber A except for the fact that the heating chamber B has a roof 32 whereby the chamber B 85 constitutes a muffle, there is no tendency for the combusted gases to enter the muffle B by reason of the fact that the combusted gases formed beneath the muffle B are caused to travel toward the charging end 90 of the furnace on their way out of the same. The result is that the atmosphere within the muffle B is substantially a dead atmosphere in which the work may be heated or soaked without coming in contact with the flow of 95 the combusted gases.

By providing separate combustion chambers for the respective heating chambers A and B the temperature of each chamber may be effectually controlled. It will be noted 100 that the work which enters the chamber A is heated by heat radiating from the floor and side walls thereof and by the circulation of the combusted gases within the tunnel of the chamber whereas in the muffle chamber B all of the heating is by radiation of heat 105 from the floor, side walls and roof of the chamber. After the work has been soaked for the requisite period the door 18 is opened and the boxes rolled out of the furnace as 110 on rollers 64 mounted on a suitable bench at the exit end of the furnace.

A carbonizing furnace constructed in accordance with the present invention satisfactorily meets all the requirements of carbonizing furnaces and may be operated at less fuel cost and constructed at considerably less expense than furnaces of the continuous muffle type. As already indicated, oxidation of the work does not occur until 115 a relatively high temperature has been reached and this fact has been taken advantage of by constructing the furnace in separate heating sections, one section of which is an open top tunnel whereby the combusted gases may flow around the work and the other of which is a tunnel which protects the work from direct contact with the combusted gases. Various changes in 120 details of construction may be made without 125 130

departing from the spirit of the invention.

What is claimed is:

1. In a furnace, the combination of a muffle, an open top heating chamber having 5 heat permeable walls, the floor and walls of said chamber forming a continuation of the floor and side walls of the muffle, a combustion chamber formed beneath the floor of said chamber, ports through which the hot 10 gases from the combustion chamber may pass upwardly exteriorly of the walls of said heating chamber to heat the same, means permitting hot gases to circulate around the muffle, the furnace at a point remote 15 from the muffle having openings through which the spent gases may pass out of the furnace.
2. In a furnace, the combination of a muffle, an open top heating chamber having 20 heat permeable walls, the floor and walls of said chamber forming a continuation of the floor and side walls of the muffle, a combustion chamber formed beneath the floor of said chamber, ports through which the hot 25 gases from the combustion chamber may pass upwardly exteriorly of the walls of said heating chamber to heat the same, means permitting hot gases to circulate around the muffle, the furnace at a point remote from 30 the muffle having openings through which the spent gases may pass out of the furnace, and means for controlling the flow of the hot gases through the ports associated with said heating chamber.
3. In a furnace, the combination of a muffle, an open top heating chamber having heat permeable walls, the floor and walls of said chamber forming a continuation of the floor and side walls of the muffle, a combustion 40 chamber formed beneath the floor of said chamber, ports through which the hot gases from the combustion chamber may pass upwardly exteriorly of the walls of said heating chamber to heat the same, a combustion 45 chamber beneath the floor of said muffle, means for directing the flow of the hot gases from the last mentioned combustion chamber exteriorly of the side walls of the muffle and towards that end of the muffle remote from 50 the heating chamber, the furnace at a point remote from the muffle having openings through which the spent gases may pass out of the furnace.
4. In a furnace, the combination of a pair 55 of heating chambers having their floor and side walls supported in spaced relation with respect to the floor and side walls of the furnace, the space beneath the floor of the respective chambers constituting independent 60 combustion chambers in which fluid fuel may be burned, said furnace having an outlet for the products of combustion adjacent one end of the furnace, that heating chamber the more remote from said outlet having a roof in spaced relation to the roof of the furnace, 65 and means permitting the products of combustion formed by the burning of fuel in said combustion chambers to flow upwardly between the side walls of the heating chambers and the side walls of the furnace. 70
5. In a furnace, the combination of a pair of heating chambers having their floor and side walls supported in spaced relation with respect to the floor and side walls of the furnace, the floor of said chambers constituting 75 the roof of independent combustion chambers in which fluid fuel may be burned for heating said heating chambers, the spaces between said side walls being in open communication with said combustion chambers 80 whereby the products of combustion may pass up between said walls, means in the roof of the furnace through which the products of combustion may pass out of the furnace, means for regulating the upward flow 85 of said gases along the side walls of one of said heating chambers, a roof for the other chamber, and means associated with the last named chamber for causing the gases to flow toward the far end thereof along its outer side walls before passing out of the furnace. 90
6. In a furnace, the combination of a muffle and an open top heating chamber, the muffle being supported in spaced relation 95 with respect to the interior walls, roof and floor of the furnace and the side walls and floor of the heating chamber being in spaced relation with respect to the walls and floor of the furnace, mutually independent combustion chambers beneath the floor of the muffle and heating chamber, means for introducing fluid fuel into said combustion chambers, passages associated with the exterior side walls of said muffle through 100 which the products of combustion formed in said combustion chambers may pass from the latter toward the end of the muffle remote from the heating chamber, passages in the furnace roof adjacent the entrance to 105 said heating chamber through which the products of combustion from both combustion chambers may pass out of the furnace, and means associated with the side walls of the heating chamber for controlling the 110 flow of products of combustion from the combustion chamber associated with the heating chamber. 115
7. In a carbonizing furnace, the combination with a furnace chamber, of a trough arranged in spaced relation to the floor and side walls of the chamber, a heating chamber in open communication with one end of said trough, means for heating said heating chamber, means for applying heating gases 120 between the floor of said chamber and the bottom of said trough, and means for inducing the spent heating gases to flow in a direction away from said heating chamber and out of the furnace chamber. 125

8. In a carbonizing furnace, the combination with a furnace chamber, of a heating trough having its side walls spaced from the side walls of said chamber, a heating chamber in open communication with one end of said trough, means for heating said heating chamber, means for supplying heating gases to the trough and exteriorly of the side walls thereof, and means for inducing the spent heating gases to flow in a direction away from the heating chamber and out of the furnace chamber.
9. In a carbonizing furnace, the combination of a heating chamber, a heating trough communicating with one end thereof, means for surrounding said trough with heating gases, and means for inducing said heating gases to flow in a direction away from said heating chamber.
10. In a carbonizing furnace, the combination of a heating chamber, means for heating said chamber, a heating trough communicating with one end of said chamber,
- means for completely surrounding said trough with heating gases, and means for inducing said heating gases to flow in a direction away from said heating chamber. 25
11. A furnace as claimed in claim 1, characterized by the fact that said point from which the products of combustion escape is 30 in the roof of the furnace.
12. In a furnace, the combination of a muffle, an open top heating chamber having heat permeable walls, the floor and walls of said chamber forming a continuation of the 35 floor and side walls of the muffle, a combustion chamber formed beneath the floor of said chamber, ports through which the hot gases from the combustion chamber may pass upwardly exteriorly of the walls of 40 said heating chamber to heat the same, and means permitting hot gases to circulate around the muffle.

In testimony whereof I affix my signature.

WILLIAM M. HEPBURN.
